UNITED STATES PATENT OFFICE.

HENRY WILLIAM CLOTHIER, OF HEBBURN-ON-THE-TYNE, ENGLAND, ASSIGNOR TO
A. REYROLLE AND COMPANY LIMITED, OF HEBBURN-ON-THE-TYNE, DURHAM,
ENGLAND.

ELECTRIC SWITCH-GEAR.

1,357,846.

Specification of Letters Patent.

Patented Nov. 2, 1920.

Application filed November 3, 1917. Serial No. 200,170.

To all whom it may concern:

Be it known that I, HENRY WILLIAM CLOTHIER, a subject of the King of England, and residing at Hebburn-on-the-Tyne, Durham, in England, have invented certain new and useful Improvements in Electric Switch-Gears, of which the following is a specification.

This invention relates to improvements in electric switch gear of the armored draw-out type comprising two distinct portions one carrying the immersed main switch and one set of auxiliary contacts this portion being movable relatively to a fixed portion which comprises the bus-bars and like stationary connections and a set of auxiliary contacts coöperating with the other set.

In some switches of this type the connections from the bus-bars are carried to contacts within insulators of bell shape which fit over plug shaped insulators carrying the coöperating contacts which are movable on a carriage having a substantially horizontal path of motion. Thus the contacts have to be insulated by porcelain or other solid material and air and when very high voltages are employed there is a risk of static discharges occurring in the inclosed air spaces and such discharges may weaken the insulation.

It is to be understood that the contacts herein referred to as the auxiliary contacts are not those at which the main break takes place for those, in the type of switch gear referred to, are immersed in insulating liquid. This distinction is illustrated in the diagram forming Figure 1 of the accompanying drawings where A is the main break and B and B' the auxiliary breaks. The parts between the auxiliary breaks B and B' constitute what is termed for the purpose of this specification the movable portion of the switch gear.

The object of the present invention is to arrange and combine the movable and fixed portions of switch gear of the armored draw-out type so that the auxiliary contacts, when closed, shall be immersed in oil or other insulating liquid. Further the arrangement is preferably such that the live auxiliary contacts *i. e.*, those connected to the bus-bars and like stationary conductors

are always immersed in the insulating liquid.

It has been proposed to construct switch gear for a divided bus-bar system in which the separating switches and all other contacts are immersed in insulating liquid but such switch gear is not of the type herein referred to.

In the accompanying drawings, Fig. 1 is the diagram previously mentioned.

Figs. 2 and 3 are vertical sections through one construction of switch gear according to this invention, and

Fig. 4 is a vertical section of another construction of switch gear also according to this invention. All the figures are diagrammatic only such parts being shown as are necessary for the understanding of the invention.

With reference first to Figs. 2 and 3, Fig. 2 shows the movable part of the switch gear only and this portion is indicated in dotted lines in Fig. 3 the remaining portion of that figure showing in full lines the fixed portion of the switch gear.

In Fig. 2 C, C' are the auxiliary contacts carried by the movable portion of the gear which comprises a tank D adapted to contain oil or other insulating liquid in which is immersed the main break switch E. The opening and closing of this main break switch may be accomplished by any convenient and known mechanism such means being merely indicated diagrammatically at F. The fixed portion of the switch gear (Fig. 3) comprises a suitable standard or support G carrying tanks or chambers H H' for insulating liquid in which liquid the auxiliary socket contacts J, J' are immersed which coöperate with the plug auxiliary contacts C and C' on the movable portion. The auxiliary contact J is connected to a bus-bar K in a chamber beneath the contact and the auxiliary contact J' on the other side of the fixed portion is likewise joined to stationary conductors which may be in circuit with transformers or the like. It will be noticed that the two auxiliary contacts J, J' which are "live" that is to say which are joined to the bus-bars and transformers or like stationary conductors, are always im-

mersed in insulating liquid. Fig. 3 shows the movable portion of the switch with its auxiliary contacts C, C' just above the co-operating fixed auxiliary contacts J and J' and a vertical downward movement of the movable portion would bring the plug contacts C, C' into engagement with the socket contacts J and J'.

In the construction of switch gear shown in Fig. 4 the tank D² in which the main break switch E² is immersed in insulating liquid forms part of the fixed portion of the switch gear the side tanks H⁴ and H⁵ also being fixed. The tank H⁴ contains an auxiliary contact J⁴ connected say to a bus-bar and the tank H⁵ an auxiliary contact J⁵ connected to a transformer or other stationary conductor. The movable portion of the gear in this construction comprises the main break switch E² with the conductors E³ and E⁴ leading to it and the auxiliary contacts C⁴ and C⁵ with their connections to the conductors E³ and E⁴. The movable portion also comprises the covers N and N' which support between them an outlet or vent O through which vapors caused by the breaking of the main switch may pass out. It will be seen that the live auxiliary contacts J⁴ and J⁵ are always immersed in the insulating liquid in the tanks H⁴ and H⁵ and that all the contacts are so immersed when the switch gear is in its closed position as indicated in Fig. 4. In this construction the connection between the co-operating sets of auxiliary contacts C⁴ and J⁴ and C⁵ and J⁵ instead of being a plug and socket connection as in the other constructions previously described is shown as a brush contact R which can itself be moved by means of say a cord S.

The various covers or chambers over the permanent connections may be filled with some solid insulating material as indicated in the figures.

What I claim as my invention and desire to secure by Letters Patent is:—

1. In electric switch gear of the armored draw-out type the combination of a fixed portion, a central oil containing tank or chamber adapted to contain a main switch, a tank or chamber at each side of said central tank and adapted to contain an insulating liquid, an auxiliary contact immersed in the liquid in each side chamber, a portion movable relatively to said fixed portion, a main switch mounted on said movable portion, and auxiliary contacts mounted at each side of said movable portion so as to co-operate with the auxiliary contacts mounted on the fixed portion, the parts being so disposed and arranged that both sets of auxiliary contacts and the main switch are immersed in insulating liquid when the said auxiliary contacts are closed.

2. In electric switch gear of the armored draw-out type the combination of a fixed portion comprising a central tank and two other tanks one on each side of it all adapted to contain insulating liquid, an auxiliary contact mounted on each side of the fixed portion and always immersed in the liquid in the corresponding side tank, a portion movable relatively to the fixed portion, a main switch carried by the movable portion and immersed in the insulating liquid in the central tank and auxiliary contacts also carried by said movable portion and co-operating with the auxiliary contacts mounted on the fixed portion said movable auxiliary contacts being oil immersed when they are closed.

In testimony whereof I have signed my name to this specification in the presence of two subscribing witnesses.

HENRY WILLIAM CLOTHIER.
